(57) **CLAIM**

The ornamental design for a cord connection securing clip, as shown and described.

DESCRIPTION

FIG. 1 is a front view of a cord connection securing clip showing my new design, a rear view being identical thereto; FIG. 2 is a left side view of the cord connection securing clip, a right side view being identical thereto; FIG. 3 is a top view of the cord connection securing clip; FIG. 4 is a bottom view of the cord connection securing clip; and, FIG. 5 is a top front side perspective view of the cord connection securing clip in use. The broken lines shown in FIG. 5 represent unclaimed subject matter and form no part of the claimed design.

1 Claim, 4 Drawing Sheets**FIG. 1**

FIG. 2

FIG. 5
